UNITED STATES PATENT OFFICE.

IDA D. WILDER, OF LAKE CITY, FLORIDA.

SANITARY SEAT COVER.

Application filed June 7, 1920. Serial No. 387,080.

To all whom it may concern:

Be it known that I, IDA D. WILDER, a citizen of the United States, residing at Lake City, in the county of Columbia and State of Florida, have invented new and useful Improvements in a Sanitary Seat Cover, of which the following is a specification.

The present invention relates to improvements in sanitary seat covers.

10 The main object of the invention is to provide a sanitary cover preferably of paper, which when folded will form a substantially square package that may be vended and handled in a convenient manner.

15 Various other objects and advantages of my invention will become apparent during the continuance of the following description.

In the drawings:—

Fig. 1 is a view in top plan showing the 20 cover in blank form.

Fig. 2 is a view in plan showing the cover folded once along its longitudinal axis which is the first step in folding the same into packet form.

25 Fig. 3 is a view of the cover showing the same folded on line B—B of Fig. 2 which is the second step.

Fig. 4 is a view of the cover folded on line C—C of Fig. 3 which is the third step.

30 Fig. 5 is a view showing the cover folded on line D—D of Fig. 4 which is the fourth step.

Fig. 6 shows the cover in a completely folded position.

35 In reducing my invention to practice I provide a cover consisting of a body portion 10 having front and rear retaining flaps 11 and 12 substantially of the form shown in Fig. 1. However, the dimensions and shape 40 of the body portion and the front and rear flaps may be varied without departing from the spirit and scope of the invention.

The rear flap 12, shown in Fig. 1 is provided at a point slightly off center, with a 45 second flap 13 whose one face may be pro-

vided with adhesive material so that when the cover is in a completely folded position the second flap may be employed to hold the same in such folded position or in other words in a compact packet form.

The first step in folding the cover into packet form is to fold the cover on line A—A of Fig. 1 into the position shown in Fig. 2. It is then folded transversely on the line B—B of Fig. 2 into the form shown in Fig. 3. It is then folded longitudinally on the line C—C of Fig. 3 into the form shown in Fig. 4 and, finally on the line D—D of Fig. 4 into the form shown in Fig. 5. When the cover is folded into this position the flap 13 may be used to retain the same in compact form as clearly shown in Fig. 6.

After the cover has been folded into the form shown in Fig. 6 the packets may be vended or otherwise handled conveniently and the person procuring the packet can quickly and easily tear the flap 13 and unfold the cover into an operative position.

From the above it is believed that the advantages and novel features of my invention will be readily understood and therefore further detailed description is deemed unnecessary.

What is claimed is:—

A sanitary seat cover comprising a body portion adapted to fit a conventional toilet seat, a flap formed at the front end of said body portion adapted to be folded beneath the toilet seat, a flap formed at the rear end of said body portion, a securing flap formed on said last named flap, and adhesive material provided on said securing flap whereby when folded into packet form said securing flap may be utilized to retain it in said position.

IDA D. WILDER.
